SOFA-BED MECHANISM HAVING CONTINUOUS-ACTION LINKAGE SYSTEM

Louis Pokorny, Jr., Ronkonkoma, N. Y., assignor of one-third to Louis Pokorny, Ronkonkoma, and one-third to John M. Pokorny, Bellport, N. Y.

Application October 31, 1956, Serial No. 619,473

13 Claims. (Cl. 5—13)

This invention relates generally to sofa-beds, and has particular reference to an adjustable structure which in a closed position defines a sofa and may be adjusted into an open position to form a bed.

The invention is specifically concerned with improvements in foldable sofa-bed frames or mechanisms of the type in which a plurality of articulated sections are pivoted to one another in succession and comprise (in the folded sofa condition) a rear section, a lower horizontal section, a front vertical section, and an upper horizontal section, these sections being foldable and unfoldable between the sofa position and an extended bed position in which the sections lie in horizontal alignment. A mattress is associated with the frame in such a way that it lies flat on the extended frame when the device is opened to define a bed, and doubles upon itself when the frame is folded to define a sofa.

It is a general object of the invention to provide a mechanism of this kind with an improved continuous-action linkage system whereby the parts are constrained always to fold and unfold in accordance with a continuous predetermined pattern of movement. This achieves numerous advantages among which are an elimination of sliding parts such as pin-slot engagements which impose friction load and frequently cause jamming and inconvenience, and an avoidance of the undesirable necessity for the operator himself to bring parts into or out of some special relationship as a prerequisite to further movements of the frame in the contemplated proper manner.

A more particular object of the invention is to form and arrange the elements of the linkage system, and the various pivot axes involved, in such a way that the force applied by the operator is automatically effective to maximum advantage upon successive subordinate groups of parts of the mechanism as it is opened or closed. In this way the applied force is desirably spread out, as a result of which less force is needed than is ordinarily required for manipulating bed frames of this type, and better mechanical advantages are achieved. The automatic concentration of force and action to successive stages of the movement is effective also to enhance the stability of the mechanism during its adjustments, and is beneficial in facilitating the movement of the folded mechanism with respect to the sofa frame during the initial withdrawal of the parts from, and the final restoration to, the fully folded sofa position. During this critical period there is a necessity for avoiding undesired contact with the sofa back and the front board, each or both of which may be of upholstered character in accordance with current styles. The improved mechanism permits the folded parts to move safely past these upholstered regions without requiring any special locking means to hold the frame parts together, or any special means for swinging or otherwise moving aside either the sofa-back or the front board.

A general objective of the invention is to provide an improved foldable sofa-bed in which the mechanism is easier to open and close, more readily adjustable with

2

a minimum of applied force, less frictional and hence quieter, smoother, and longer wearing, and more reliable in operation. The special linkage system which is a characterizing feature of the invention consists, in brief, of a first lever fulcrumed to the lower horizontal section, a second lever fulcrumed to the front vertical section, a rear link extending between the rear section and one arm of the first lever, the other arm of the first lever being pivoted to one arm of the second lever, and a front link extending between the other arm of the second lever and the upper horizontal section. By a linkage system of this kind, with the various pivot axes arranged in such a way that critical alignments automatically occur in a predetermined fashion in the extended and in the folded conditions of the mechanism, it is possible to achieve a variety of advantages having far-reaching effects in commercial practice. For example, by means of this invention it is a practical possibility, if desired, to employ a bigger mattress, to fold it more readily, and to collapse the mechanism expeditiously into a folded state of less height or of reduced depth or both. The ease of folding the mattress makes it possible to employ the mattress sidewise, i. e., with its long axis parallel to that of the sofa, whereby the invention is readily applicable to the more compact sofa-beds of relatively long character, in which the bed axis extends lengthwise of the sofa instead of at right angles to it.

Other features of the invention reside in the provision of a special rear leg, and means for automatically moving it, whereby the structure is stabilized in an unusually effective manner during the adjustment procedures; in the provision of a special means for depressing the upper or movable part of the front board of the sofa when the mechanism is extended to define the bed; and in the provision of an improved spring support, especially applicable when the invention is embodied in the longer type of sofa, and a means for automatically depressing the spring support when the mechanism is adjusted to the sofa condition.

These objects and advantages, and such other objects and advantages as may hereinafter appear or be pointed out, can be practically achieved in the several embodiments of the invention exemplified in the accompanying drawings, in which—

Fig. 1 is an end view of a device constructed in accordance with the present invention, the sofa-bed body, the cushions of the sofa, and the mattress of the bed, being shown in dot-and-dash lines, the mechanism being in its fully folded position;

Fig. 2 is a fragmentary enlarged view of part of the mechanism in its fully folded condition;

Fig. 3 is a view similar to Fig. 1, showing the mechanism in an initial stage of its unfolding movement;

Figs. 4 and 5 are views similar to Figs. 1 and 3, but on a reduced scale, showing the mechanism in successive stages of opening, the bed being fully extended in Fig. 5;

Fig. 6 is a fragmentary top view of Fig. 5;

Fig. 7 is a view similar to Fig. 1 showing a modified construction in which the features of the invention are embodied in a sofa-bed device whose sleeping surface has a longitudinal axis parallel to the long axis of the sofa;

Fig. 8 is a fragmentary view of part of the mechanism shown in Fig. 7, with parts omitted to reveal structure that would otherwise be hidden;

Figs. 9, 10 and 11 are views similar to Fig. 7 showing the mechanism in successive stages of opening, Fig. 11 being a view in which the mechanism is in its fully extended position; and

Fig. 12 is a fragmentary top view of Fig. 11.

The sofa body within which the mechanism is mounted includes the usual upholstered back 20, sides 21, remov-

able seat cushions 22, legs 23, and a "front board" comprising a lower part 24 that remains fixed in position, and an upper part 25 that is automatically moved aside or carried along with the mechanism when it is unfolded. In many cases, the front board and the sides of the sofa body are upholstered.

The mechanism consists essentially of four sections, pivoted to one another in series. When the device is fully opened (Figs. 5 and 6) the mattress support is made up of these four sections arranged in substantially horizontal alignment.

In the closed or folded position of the device, these four sections assume a compacted relationship; and for facility in terminology the sections will be referred to herein by terms based upon their respective dispositions in the closed condition. Thus, section 30, which is nearest the back of the sofa body 20, will be referred to as the "rear section"; section 40, which is substantially horizontal, will be referred to as the "lower horizontal section"; section 50, which is at the front of the sofa body, will be referred to as the "front vertical section"; and section 60 will be termed the "upper horizontal section".

In the embodiment of the invention depicted in Figs. 1-6, the rear section 30 is angular, having an arm 35 pivotally mounted at 36 on a fixed supporting bar 37 secured to the sofa body 20. The lower end of the rear section 30 is pivoted at 38 to the rear end of the lower horizontal section 40. The forward end of section 40 is pivoted, at 41, to the lower end of the front vertical section 50; and the upper end of the section 50 is pivoted, at 51, to the front end of the upper horizontal section 60.

The parts 30, 40, 50 and 60 have been spoken of as "sections" rather than mere members because each section has companion parts or members at the respective right and left ends of the sofa body. The particular sections 30, 40, 50 and 60 shown in the present drawings, represent only the companion parts at the near end of the sofa body. The corresponding parts of the sections at the opposite end of the sofa have been omitted from the drawings, since they are mere counterparts of those shown.

The elements forming the various sections are preferably angle irons, and are provided with well-known flanges or other suitable stop means to limit unfolding movement to the aligned relationship. Extending transversely across the device at suitable intervals are cross-bars, such as those shown at 31 and 32, to hold the parts of each section together as a structural unit. Similar crossbars, such as those designated 33 and 34, unite other parts of the mechanism transversely across the device as a whole.

Also extending transversely is a bed spring 70 (Fig. 6) adapted to support a mattress 80 (shown in dot-and-dash lines). The spring may be supported in any well known manner between the opposite members of the sections of the mechanism. The mattress 80 is retained in folded condition within the mechanism when the device is in the sofa position.

In the embodiment illustrated in Figs. 1-6, the longitudinal axis of the mattress is at right angles to the longitudinal axis of the sofa. Mattresses currently in common use are usually 72 or 74 inches long, and it is this length which extends between the mattress ends designated 81 and 82 in Fig. 5. The width of the mattress is usually between 54 and 60 inches, and in the device shown in Figs. 1-6 the arms 21 of the sofa are spaced apart by an amount just slightly greater than this.

The initial part of the unfolding movement of the mechanism (compare Figs. 1 and 3) involves a swinging movement of the rear section 30 about the fixed pivot 36. The folded bundle of mechanism follows the arcuate movement of the pivot 38 at the rear, and is governed at the front by the simultaneous swing of the elevator arm or lever 42 about a fixed pivot 46. This pivot is at one end of a fixed bracket 43 secured to the sofa frame. Extending from the rear end 49 of the bracket 43 for-

wardly to a pivoted connection with the elevator arm 42 at 48 is a coiled tension spring, or pair of springs, 47. This spring is in a stressed condition when the parts are in the relationships of Figs. 1 and 5, and it is in its least stressed condition when the parts are just about to assume the relationship of Fig. 4. In this way the spring facilitates both the unfolding and the folding manipulations.

The upper or free end of the elevator arm may be articulated to the mechanism at any of several selected points. In the construction shown a pivot connection is established at 91 between the free end of the elevator arm 42 and a link 90 whose function and mode of operation will be presently described.

The special linkage system of the invention, by means of which the movements of the various sections are automatically controlled, constraining the parts always to the same predetermined pattern of movement, consists essentially of a first lever 100, a second lever 101, the rear link 90, and a front link 102. Each of the levers 100 and 101 is a lever of the first class, that is, its fulcrum is at a midportion of the lever, as best indicated in Figs. 4 and 5. The lever 100 is fulcrumed at 103 to the lower horizontal section 40, near the pivot 41 between this section and the adjacent front vertical section 50. The lever 101 is fulcrumed at 104 to the front vertical section 50. The rear arm of the lever 101 is pivotally connected at 105 to the adjacent arm of the lever 100. The other arm of the lever 100 is pivoted at 106 to the forward end of the link 90. The rear end of this link is pivoted at 107 to the rear section 30. The forward arm of the lever 101 is pivoted at 108 to the rear end of the front link 102, and the forward end of the latter is pivotally connected at 109 to the upper horizontal section 60 in the region adjacent to the pivot 51 between the sections 50 and 60.

Before describing the features of this linkage system and of the form and arrangement of the parts and their pivotal relationships, reference will be made to the rear and front legs of the bed, and the mechanism that controls the movements of the upper front board 25.

Pivoted to the lower horizontal section 40 at a point 52 close to the pivot 41 is a rear leg 53 adapted to swing between the inoperative position shown in Figs. 1-3 (extending rearwardly and lying closely adjacent and parallel to the lower horizontal section 40) and the vertical operative position shown in Fig. 5. The movements of this leg are controlled by an actuating link 54 pivoted at one end 55 to the first lever 100 and at the opposite end 56 to the leg 53.

Pivoted to the upper horizontal section 60 at a point 61 is a front leg 62 adapted to swing between the collapsed inoperative position of Figs. 1-3 (lying adjacent and parallel to the section 60) and the operative bed-supporting position of Fig. 5. The movements of the leg 62 are controlled by an actuating link 63 extending from the front link 102 of the special linkage system. More particularly, one end of the link 63 is pivoted at 64 to the link 102, while the other end is pivoted at 65 to the leg 62.

The movable front board 25 is pivoted at a point 71 near its upper edge to an actuating link 72 extending from the link 63 and pivoted to the latter at 73. Adjacent to its lower edge the board 25 is pivoted at 74 to a leg stump 75 that is pivotally anchored at 76 to the front vertical section 50 at a point adjacent to the pivot 51. The leg stump 75 is pivoted at 77 to an actuating link 78 whose opposite end is pivoted at 79 to the front link 102 of the linkage system.

In adjusting the parts from the sofa position to the extended bed position, the operator lifts upwardly on the movable front board 25. Because of the assistance afforded by the spring 47, the parts are rapidly and with little effort brought to and through the position of Fig. 3. It will be observed that the bundle of links and elements

is still in a relatively compact relationship, as a result of which the bundle freely clears the lower part of the upholstered back of the sofa, and the upper edge of the fixed front board 24. As an advancing pull is exerted by the user, the sections 30 and 40 gradually come into horizontal alignment as shown in Fig. 4. During this time the rear link 90 moves rearwardly relative to the section 40, thus pulling the first lever 100 in a counter-clockwise direction. This has brought about a rapid descent of the rear leg 53 which encounters the floor and affords desirable support to prevent the weight of the mechanism and bedding from tilting the entire device forwardly. At the same time, the second lever 101 has been moved in a counter-clockwise direction relative to the section 50 to which it is fulcrumed. This imparts a pushing force upon the front link 102 whereby the upper section 60 has been advanced to the vertical position shown in Fig. 4. At the same time, the front leg 62 has been swung out into readiness for engagement with the floor, and the movable front board 25 has been moved downwardly away from the bed sections. The final adjustment of the parts from the relationship of Fig. 4 to that of Figs. 5 and 6 is relatively simple, since the sections 30 and 40 are already in alignment, and the rear leg 53 is already operative to afford support.

During the closing of the device, the procedure is reversed. With relatively little effort the user lifts up upon the free end of the section 60, and the parts readily adjust themselves into the relationship of Fig. 4. During this time, the force exerted by the user is obviously effective upon a subordinate bundle of elements and links, the sections 40 and 30 remaining in horizontal alignment, and the leg 53 remaining effective, until the device starts to close beyond the position of Fig. 4. During the adjustment of the parts from the position of Fig. 4 to that of Fig. 3, the mattress is folded upon itself and the bundle of sections and other parts is automatically brought into the compact relationship, whereby a continued rearward push will move the compacted bundle over the front board 24 and past the upholstery at the back, into the fully compacted sofa position of Fig. 1.

During these adjustments of the parts, both in the unfolding and the folding process, the movements automatically follow a predetermined pattern over which the operator has no control. Therefore, for proper functioning, it is not incumbent upon the user to bring any of the parts into or out of any special relationship or latched or interengaged condition, as a prerequisite to further folding or unfolding in proper contemplated manner. Moreover, there is an automatic concentration of the applied force to successive subordinate groups of elements, whereby the effort called for in opening and closing the device is spread out and is thus minimized. As a result, with devices conforming in size to existing sofa-beds, the effort required in using the present device is less than that ordinarily called for. In the alternative, by the exertion of the same effort, a mechanism of larger dimensions or (of more importance) a mechanism employing a mattress of larger dimensions, or with heavier bedding, can be adjusted with only the usual amount of force.

These advantages are attributable, in part, to the arrangement and cooperation of the special linkage system hereinbefore described, and in part to the special formation and arrangement of the levers and links of this system, especially the location and the relationships of the pivot axes. These special relationships are as follows:

(First) In the folded condition of the mechanism (see Figs. 1-3) there is an alignment of (a) the pivot 105 connecting the first and second levers 100, 101, (b) the fulcrum 103 securing the first lever 100 to the lower horizontal section 40, and (c) the fulcrum 104 connecting the second lever 101 to the front vertical section 50. The reason this is important is that during the earlier stages of the movement of the rear link 90 relative to the

section 40, the lever 100 moves through a relatively large angular distance while the lever 101 is rocked through a relatively small angular distance. This means that the sections 30 and 40 can be brought rapidly into the aligned relation of Fig. 4 without materially affecting the relatively compacted relation of the sections 50 and 60, this relationship being maintained (to a substantial extent) until the parts are moved further beyond the relationship of Fig. 4.

5 10 Also, the angular movement of the actuating link 54 (controlling the rear leg 53) is relatively small even though the first lever 100 moves through a relatively large angle. As a result, the leg 53 remains in the withdrawn relationship shown in Figs. 1-3 until after the bundle of elements 15 has jumped over the fixed front board 24; and as soon as this stage of movement has been reached the leg 53 comes down into the position of Fig. 4 with relatively great rapidity, to afford the support that is needed at that time.

(Second) In the closed condition, there is an alignment 20 of (1) the pivot 108 connecting the lever 101 to the front link 102, (2) the fulcrum 104 connecting the lever 101 to the front vertical section 50, and (3) the pivot 109 connecting the front link 102 to the upper horizontal section 60. The importance of this lies in the fact that the 25 initial angular movements of the lever 101 bring about very little, if any, advancement of the front link 102. Since it is this advancement that brings about an adjustment of the sections 50 and 60 from the perpendicular relationship of Fig. 3 to the aligned relationship of Fig. 5, the alignment of the parts 50 and 60 is effectively postponed until after the mechanism passes through the stage 30 of Fig. 4.

(Third) In the extended condition of the mechanism 35 there is an alignment of (I) the pivot 108 connecting the lever 101 to the front link 102, (II) the pivot 51 connecting the front vertical section 50 to the upper horizontal section 60, and (III) the pivot 109 connecting the front link 102 to the section 60. The importance of this 40 lies in the fact that during the initial stage of the closing operation a large angular movement of the section 60 takes place before the front link 102 becomes effective to rotate the lever 101. As a result of this the parts are readily moved into the partially closed position of Fig. 4 without causing any action to take place among the 45 elements affecting sections 40 and 30.

(Fourth) During the extended relationship of the parts 50 of the mechanism, there is an alignment of (A) the pivot 105 connecting the levers 100, 101, (B) the pivot 41 connecting the lower horizontal section 40 to the front vertical section 50, and (C) the fulcrum 104 connecting the lever 101 to the section 50. This alignment is important since it allows a large angular movement of the front vertical section 50 to take place before the rear arm of the lever 101 becomes materially effective in imparting 55 a clockwise push upon the lever 100. For this reason the sections 50 and 60 may be readily adjusted beyond the position of Fig. 4 and toward the position of Fig. 3 without materially disturbing the alignment between the sections 30 and 40, i. e., the final adjustment of the sections 60 60 and 40 into the perpendicular relationship of Fig. 3 is postponed toward the later part of the stage of movement from Fig. 4 to Fig. 3.

These advantages, and others as well, can be achieved 65 in a device in which the mattress is laid the other way, i. e., in which the longitudinal axis of the mattress is parallel to the longitudinal axis of the sofa. Several problems are imposed upon the designer in endeavoring to do this. For example, it is not sufficient merely to employ the conventional mechanism and to lay the mattress at right angles, since this would leave a highly undesirable gap between one side edge of the mattress and the back of the sofa when the device is in the bed condition. Also, the folding of a mattress along a lengthwise line of fold 70 75 imposes a far greater load upon the user than the conven-

tional folding along transverse lines. The employment of the present improved linkage system affords a means to overcome these difficulties, and to achieve additional benefits. One way of accomplishing these desirable results is depicted in Figs. 7-12.

Referring for the moment to Fig. 11, it should be noted that the distance between the mattress ends 181 and 182 is the narrower dimension, or width, of the mattress 180. In terms of mattress sizes currently in common use, this would be in the range of 54 to 60 inches. The provision of a mechanism of the character described, having a correspondingly shortened length when in its extended condition, is brought about, in part, by materially shortening the length of the rear section. This has numerous advantages, especially in connection with the styling of the upholstery and other external features of the sofa; but it also imposes special problems arising from the fact that the swinging movements of the rear section are affected by its shortened length. The basic sofa-bed mechanism, and the special linkage system, are the same as in Figs. 1-6, but modified in several respects to overcome these difficulties.

The rear section 130 is in this case pivoted at its upper end 136 to a fixed bracket 137 secured to the sofa body in a position lying in its entirety below the level of the sofa seat. This accords the designer more freedom in styling the sofa back 120 and the sides 121 of the sofa.

At its lower end, the section 130 is angled rearwardly and is pivotally connected at 138 to the lower horizontal section 140. In the folded position of the mechanism (Fig. 7) the rear section 130 slants rearwardly downward, and the pivot 138 preferably lies an appreciable distance to the front of the rear end of the section 140. A pivot 141 connects the front end of the section 140 to the front vertical section 150, and this section is in turn pivoted at 151 to the upper vertical section 160.

An elevator arm 142 is pivoted at 146 to a fixed bracket 143; and a spring or springs 147 extend between the pivot point 148 on the arm 142 to the rear fixed anchorage 149. The upper end of the elevator arm 142 is pivoted at 191 to the rear link 190 of the special linkage system; although, as pointed out in connection with Figs. 1-6, the elevator arm may be connected to other parts of the mechanism, e. g., the lower horizontal section 140, if desired.

The sofa body of Figs. 7-12 is provided with a fixed lower front board 124 and an upper movable front board 125. In this case, however, the board 125 is rigidly secured to the front vertical section 150, at a sufficient distance from the latter to make it unnecessary for special mechanism to be provided in order to lower the part 125 from the mattress-supporting plane when the device is used as a bed. It is to be observed, also, that the legs 123 of the sofa body are longer than those of Figs. 1-6, which is a styling advantage because it helps to conceal the circumstance that a folding mechanism is housed within the sofa body.

The linkage system comprises the rear link 190, the first lever 200, the second lever 201, and the front link 202. The lever 200 is fulcrumed at 203 to the lower horizontal section 140, and the lever 201 is fulcrumed at 204 to the front vertical section 150. The levers are pivoted together at 205. The link 190 is pivoted at 206 to the lever 200, and at its rear end it is pivoted at 207 to the rear section 130. The front link 202 is pivoted at 208 to the lever 201, and is pivoted at 209 to the upper horizontal section 160.

It will be readily recognized that the levers and links of the linkage system are essentially the same as those hereinbefore described in connection with Figs. 1-6. The lever 201 is shaped somewhat differently, but functions the same as the lever 101. The same is true with respect to the lever 200, which functions the same as the lever 100 but differs in the fact that there is no articulation to a leg-actuating link.

The rear leg is not as important in this construction as in that of Figs. 1-6, because the tendency toward imbalance of the device is not as great, during the opening movements of the mechanism. Also, by lengthening the legs 123 of the sofa body, the provision of a rear leg for the mechanism requires a mounting and actuation of such a leg in a manner different from that shown in Figs. 1-6. The leg 153 is in this case pivoted near the rear end of the section 160. In the construction shown, the pivot point is at 209, which is the point at which the front link 202 connects to the section 160. It is not essential that these two pivots be in coincidence, however. The actuation of the leg 153 from a position lying alongside the section 160 (see Figs. 7-9) to the operative position of Fig. 11 is brought about by a fan-like cluster of short links 110, 111, and 112, these links being pivoted together at 113. The link 112 has its free end pivoted at 114 to the leg 153; the link 111 has its free end pivoted at 115 to the section 160; and the link 110 has its free end pivoted at 116 to an actuating link 163. The latter link is connected at its rear end 164 to the link 202, and at its front end 165 to the front leg 162. This leg is pivoted to the section 160 at 161 and swings from the inoperative position shown in Figs. 7-9 to the operative position shown in Fig. 11.

Because of the relatively great distance between the sides 121 of the sofa, it is desirable that the bed spring 170 and the sofa seat above it be given added support in the longitudinal direction of the sofa when the parts are in the compacted or folded sofa position. To achieve this result, a special retractable sofa seat support 83, preferably a tubular metallic rod or the like, is arranged in parallel relation to the sofa axis and located below the bed spring 170. The support 83 is articulated to the lower horizontal section 140, and a means is provided for moving the support 83 between the elevated position shown in Figs. 7-9 to the lowered position shown in Fig. 11. One way to accomplish this is to provide an arm 84 that carries the support 83 and is pivoted at 85 to the lower horizontal section 140; and an arm-moving element 86 pivoted at 87 to the arm 84 and extending between the arm 84 and the rear link 190, to which it is pivoted at 88.

The special alignments of pivot axes hereinbefore described and discussed in connection with Figs. 1-6 is effective, also, in Figs. 7-12; and the advantages of these several special alignments are the same as previously pointed out. Briefly, it is to be observed that in the folded condition of the mechanism there is an alignment of pivots 205, 203, and 204; also an alignment of pivots 208, 204, and 209. In the extended condition of the mechanism, there is an alignment of pivots 209, 151, and 208; also an alignment of pivots 204, 141, and 205.

In the device shown in Figs. 7-12, there is a further special alignment of pivots which has a beneficial effect upon the operation of the mechanism. This alignment exists in the folded condition of the mechanism (Fig. 7) and involves the location of the pivot 207 connecting the rear link 190 to the rear section 130. It is to be observed that the pivot 207 lies between and in alignment with (i) the pivot 138 connecting the sections 130, 140, and (ii) the pivot 206 connecting the rear link 190 to the lever 200. The importance of this relationship of parts lies in the fact that there is very little relative movement between the rear link 190 and the lower horizontal section 140 during the swinging movement of the rear section 130 from the position of Fig. 7 to that of Fig. 9. Hence the unfolding of the mechanism (brought about by a rearward movement of the link 190 relative to the section 140) is postponed until the bundle of elements has risen forwardly to the position of Fig. 9. It is only at this time that the mechanism has cleared the lower end of the upholstered back 120, and has jumped over the fixed front board 124. The same advantage exists during the closing operation, since the bundle of folded elements is fully compacted before the final downward and rearward movement from

the condition of Fig. 9 to the fully folded condition of Fig. 7.

The parts designated 128, 131, and 132 are transverse reinforcements extending between the corresponding parts of the mechanism adjacent to the opposed sides 121 of the sofa.

It will be understood that many of the details herein described and illustrated are susceptible of modification without necessarily involving a departure from the spirit and scope of the invention as expressed in the appended claims.

Having thus described my invention and illustrated its use, what I claim as new and desire to secure by Letters Patent is:

1. In a sofa-bed mechanism, sections pivoted to one another in succession and comprising a rear section, a lower horizontal section, a front vertical section, and an upper horizontal section, said sections being foldable between a collapsed sofa position in which the lower and upper horizontal sections lie in superposed parallel relation, and an extended bed position in which said sections lie in horizontal alignment; and a linkage system interconnecting said sections to constrain the mechanism to fold and unfold in accordance with a continuous predetermined pattern of movement, said linkage system comprising a first lever fulcrumed to the lower horizontal section, a second lever fulcrumed to the front vertical section, each of said levers being levers of the first class, a rear link extending between the rear section and one arm of the first lever, the other arm of the first lever being pivoted to one arm of the second lever, and a front link extending between the other arm of the second lever and the upper horizontal section.

2. In a sofa-bed mechanism, the elements defined in claim 1, said links and levers and their pivots being so arranged that in the folded condition of the mechanism there is an alignment of (a) the pivot connecting the first and second levers, (b) the fulcrum of the first lever, and (c) the fulcrum of the second lever.

3. In a sofa-bed mechanism, the elements defined in claim 1, said links and levers and their pivots being so arranged that in the folded condition of the mechanism there is an alignment of (1) the pivot connecting the second lever to the front link, (2) the fulcrum of the second lever, and (3) the pivot connecting the front link to the upper horizontal section.

4. In a sofa-bed mechanism, the elements defined in claim 1, said links and levers and their pivots being so arranged that in the folded condition of the mechanism there is an alignment of (a) the pivot connecting the first and second levers, (b) the fulcrum of the first lever, and (c) the fulcrum of the second lever; also of (1) the pivot connecting the second lever to the front link, (2) the fulcrum of the second lever, and (3) the pivot connecting the front link to the upper horizontal section.

5. In a sofa-bed mechanism, the elements defined in claim 1, said links and levers and their pivots being so arranged that in the extended condition of the mechanism there is an alignment of (A) the pivot connecting the first and second levers, (B) the pivot connecting the lower horizontal and front vertical sections, and (C) the fulcrum of the second lever.

6. In a sofa-bed mechanism, the elements defined in claim 1, said links and levers and their pivots being so arranged that in the extended condition of the mechanism there is an alignment of (I) the pivot connecting the second lever to the front link, (II) the pivot connecting the front vertical and upper horizontal sections, and (III) the pivot connecting the front link to the upper horizontal section.

7. In a sofa-bed mechanism, the elements defined in claim 1, said links and levers and their pivots being so arranged that in the extended condition of the mechanism there is an alignment of (A) the pivot connecting the first and second levers, (B) the pivot connecting the

lower horizontal and front vertical sections, and (C) the fulcrum of the second lever; also of (I) the pivot connecting the second lever to the front link, (II) the pivot connecting the front vertical and upper horizontal sections, and (III) the pivot connecting the front link to the upper horizontal section.

8. In a sofa-bed mechanism, the elements defined in claim 1, said links and levers and their pivots being so arranged that in the folded condition of the mechanism there is an alignment of (a) the pivot connecting the first and second levers, (b) the fulcrum of the first lever, and (c) the fulcrum of the second lever; also of (1) the pivot connecting the second lever to the front link, (2) the fulcrum of the second lever, and (3) the pivot connecting the front link to the upper horizontal section; and in the extended condition of the mechanism there is an alignment of (A) the pivot connecting the first and second levers, (B) the pivot connecting the lower horizontal and front vertical sections, and (C) the fulcrum of the second lever; also of (I) the pivot connecting the second lever to the front link, (II) the pivot connecting the front vertical and upper horizontal sections, and (III) the pivot connecting the front link to the upper horizontal section.

9. In a sofa-bed mechanism, the combination with the elements defined in claim 1, of a rear leg pivoted to the lower horizontal section and adapted to extend rearwardly and lie adjacent to said section in the folded condition of the mechanism, and a leg-moving element extending from said first lever to said leg and pivoted at its ends to said lever and leg respectively.

10. In a sofa-bed mechanism, the combination with the elements defined in claim 1, of a front leg pivoted to the upper horizontal section and adapted to extend rearwardly relative to said section and lie adjacent to said section in the folded condition of the mechanism, and a leg-moving element extending from said front link to said leg and pivoted at its ends to said front link and leg respectively.

11. In a sofa-bed mechanism, the combination with the elements defined in claim 1, of a rear leg pivoted to the lower horizontal section and a front leg pivoted to the upper horizontal section, said legs being adapted to lie adjacent to said respective sections in the folded condition of the mechanism, and leg-moving elements controlled by said linkage system for rotating said legs into and out of operative positions at right angles to said sections.

12. In a sofa-bed mechanism, the combination with the elements defined in claim 1, of a rear leg pivoted to the lower horizontal section and a front leg pivoted to the upper horizontal section, said legs being adapted to lie adjacent to said respective sections in the folded condition of the mechanism, and leg-moving elements controlled by said linkage system for rotating said legs into and out of operative positions at right angles to said sections, the leg-moving element for the rear leg being pivoted to and controlled by said first lever, the leg-moving element for the front leg being pivoted to and controlled by said front link.

13. In a sofa-bed mechanism, sections pivoted to one another in succession and comprising a rear section, a lower horizontal section, a front vertical section, and an upper horizontal section, said sections being foldable between a collapsed sofa position in which the lower and upper horizontal sections lie in superposed parallel relation, and an extended bed position in which said sections lie in horizontal alignment; and a linkage system interconnecting said sections to constrain the mechanism to fold and unfold in accordance with a continuous predetermined pattern of movement, said linkage system comprising a first lever fulcrumed to the lower horizontal section, a second lever fulcrumed to the front vertical section, each of said levers being levers of the first class, a rear link extending between the rear section and one

arm of the first lever, the other arm of the first lever being pivoted to one arm of the second lever, and a front link extending between the other arm of the second lever and the upper horizontal section, said rear link being pivoted to said rear section at a point which in the folded condition of the mechanism lies between and in alignment with (i) the pivot connection between the rear and lower horizontal sections, and (ii) the pivot connecting the rear link to the first lever.
